CLAIM

The ornamental design for a tripod lamp, as shown and described.

DESCRIPTION

FIG. 1 is a top, rear and left side perspective view of a tripod lamp showing our new design;

FIG. 2 is a bottom, front and right side perspective view thereof;

FIG. 3 is a top, front and right side perspective view thereof;

FIG. 4 is a bottom, rear and left side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof; and,

FIG. 11 is a top, rear and left side perspective view showing the tripod lamp in a use state.

The broken lines in the drawings illustrate portions of the tripod lamp which form no part of the claimed design.

The tripod lamp is shown with symbolic breaks in its length in FIG. 11. The appearance of any portion of the article between the break lines forms no part of the claimed design.

1 Claim, 11 Drawing Sheets
